UNITED STATES PATENT OFFICE.

WILLIAM R. GORDON, OF OSCEOLA, SOUTH CAROLINA, ASSIGNOR OF ONE-HALF TO HARRY HINES AND DUNKLIN FERGUSON, OF LANCASTER, SOUTH CAROLINA.

MAIL-BAG LOCK.

SPECIFICATION forming part of Letters Patent No. 663,268, dated December 4, 1900.

Application filed December 22, 1899. Serial No. 741,317. (No model.)

To all whom it may concern:

Be it known that I, WILLIAM R. GORDON, a citizen of the United States, residing at Osceola, in the county of Lancaster and State 5 of South Carolina, have invented certain new and useful Improvements in Mail-Bag Locks, of which the following is a specification.

My invention relates to mail-bag locks, and is designed as an improvement over my former 10 patent, No. 535,001, dated March 5, 1895.

In the drawings forming part of the specification, and in which like symbols of reference represent corresponding parts in the several views, Figure 1 is a perspective view 15 of the bag, showing the mouth open. Fig. 2 is an elevation showing the sliding tongue-chain and its guide-plates. Fig. 3 is a view of the sliding tongue-chain detached; and Fig. 4 is a longitudinal sectional view at right 20 angles to Fig. 1.

1 represents the bag to which my device is applied, having the slots 2 arranged on opposite sides of its mouth, so as to register when the two sides are brought together. These 25 slots are eyeleted in the usual manner, except those passing through plates 5, which of course perform the same function as an eyelet.

3 is the flap of the bag provided with staples 4, located on the inside of the same. 30 Just beneath the flap of the bag I attach a series of plates 5, having the guiding-pins 6, which work in slots 8, formed in the tongues 9 of a chain-like slide or locking-plate 10. This locking-plate 10 slides within guiding- 35 staples 11, attached to the plates 5, and is formed of a series of links 12, 13, and 14, attached to plates 5', that carry the tongues 9. The plates 5' are connected to the links by pins 6', so that a yielding connection is secured. 40 The links 14 are longer than the other links for the purpose of accommodating the hasp 15, which is hinged at 16 to one of the plates 5

and forms a lever, by means of which the slide 10 may be reciprocated within the staples 11.

The operation of the device is as follows: 45 The flap 3 being folded over the mouth of the bag and the staples 4 passed through the slots 2 on both sides of the mouth of the same, the hasp 15 is turned upon its hinge so that the tongues 9 are drawn through staples 4, 50 and a padlock is attached to the staple passing through the hasp 15.

Having now fully described my invention, what I claim as new, and desire to secure by Letters Patent, is—

1. In a device of the character described, a reciprocable locking-plate, guides for the same, plates having a plurality of pins connecting them with the links of the locking-plate, and having slotted tongues extending 60 from the same, a hasp hinged at its inner end to the bag and having a hinged connection with the locking-plate, its inner hinge acting as a fulcrum when the locking-plate is operated, and staples attached to the bag-flap 65 adapted to be engaged by the tongues of the locking-plate.

2. In a device of the character described, a reciprocable linked locking-plate, slotted locking tongue-plates having a plurality of pins connecting them with the locking-plate, guide-pins attached to the bag and working in said slots, staples on the bag-flap, and a hasp hinged to the edge of the bag and having also a hinged connection to the locking- 70 plate, its inner hinge acting as a fulcrum 75 when the locking-plate is operated.

In testimony whereof I affix my signature in presence of two witnesses.

WILLIAM R. GORDON.
